EXTRUDING MACHINE

Vernon Royle, Paterson, N. J.

Application February 18, 1932, Serial No. 593,698

9 Claims. (Cl. 146—174)

This invention relates to an improvement in heads for extruding machines.

It has for an object to provide a device of this character which is so constructed that the parts forming the head may be separated transversely without disassembling the parts as a unit, for purposes of cleaning or replacing parts of the same, and quickly and easily returning them to operative position.

Another object consists in providing a device of this character in which the head is formed of two members hinged together so that one member may be swung outwardly away from the fixed member, thereby exposing the interior of the head.

Another object consists in providing a device of this character having a relatively thin strainer plate disposed in position on the movable member and reinforced by the member to resist any undue strain or irregularity in operation.

Another object consists in providing a device of this character having means rotatably mounted on the movable member for cutting the material transversely, when so desired, after it has passed through the head.

Another object consists in providing certain improvements in the form, construction and arrangement of the several parts whereby the above named and other objects may effectively be attained.

Machines of this character are so designed to operate on rubber compounds, including various substances, during the process of reclaiming the rubber; and these compounds and substances vary greatly in character and consistency. Consequently, it has been found that strainer heads heretofore in use have to be repeatedly taken away to be cleaned and again assembled before the machine can again be set in operation, which disassembly and assemblage consumes a considerable amount of time and labor in handling the parts. My invention is designed to overcome these disadvantages and thereby enhance the capacity of the output of the machine, as well as embody advantages inherent in the construction.

A practical embodiment of my invention is represented in the accompanying drawings, in which

Fig. 1 represents a plan view of the strainer head secured to the cylinder, the latter being broken away, and certain movable elements of the head being shown in different positions in dotted outline.

Fig. 2 represents a front elevation of the same.

Fig. 3 represents a vertical section taken in the plane of the line III—III of Fig. 2, looking in the

direction of the arrows, certain of the elements being shown in another position in dotted outline.

Fig. 4 represents a front elevation of the strainer head, showing modified form of means for transversely cutting the material passed from the head and mechanism for actuating the same, and

Fig. 5 represents a horizontal section taken in the plane of the line V—V of Fig. 4, looking in the direction of the arrows.

The cylinder of the extruding machine may be of any well-known or approved form of which the front portion only is shown and represented in the drawings by 1. The usual screw or plodder 2 is housed within the liner 3 of the cylinder, and projects therefrom for co-operation with the fixed member 4 of the strainer head. This member 4 is secured in position on the cylinder by means of a series of stud bolts 5 which extend outwardly from the cylinder 1 and register with holes formed in the face plate 6 of the member 4. Nuts 7 are provided for threading on the bolts 5 in order to secure the face plate and hence the member 4 in position on the cylinder. The member 4 includes an inner liner 8 which is shouldered at 9 to match a reduced flange 10 that projects forwardly from the bore liner 3. A suitable washer 11 may be placed between the cylinder 1 and the bore liner 3 on one hand, and the face plate 6 and the inner liner 8 on the other hand.

Suitable passages 12 are disposed in the member 4 for the circulation of a temperature controlling medium in a manner well understood in this art. The interior of the member 4 immediately in advance of the screw receiving portion expands or flares abrupt to the shoulder 13, and, in order to control the temperature at this point, I embed a tube 14 by routing or otherwise cutting out the surface of the shoulder 13 and then cover over the tube with metal or other suitable material 40 appropriately secured in place. The ends 15, 16 of the tube 14, shown in dotted lines in Figs. 2 and 3, are arranged to extend downwardly toward the outer circumference of the member and are provided with couplings 17, 18, respectively, for 45 connecting the temperature controlling medium, such, for instance, as steam or water.

The movable member of the head is denoted by 19 and has its inner circumference 20 for a short distance substantially equal to the inner 50 diameter of the shoulder 13, then it is flared forwardly and outwardly at 21, though its flare is not as abrupt as that of the interior of the fixed member 4 between the end of the screw and the shoulder 13. The movable member 19 has also 55

formed in the inner circumference 20, 21 vertical partitions 22, 23 and connecting horizontal partitions 24, 25 which serve to divide the material passing therethrough into four sections. Each 5 partition is tapered inwardly at 26 thence outwardly at 27 to allow the plastic material to flow freely therethrough.

The inner surface of the movable member 19 is recessed at 28 for the reception of a relatively 10 thin foraminous plate 29, the perforations in which are denoted by 30. This plate 29 is secured in position in the recess 28 by screws 31 and arranged to abut the vertical and horizontal partitions which prevent the plate from buckling 15 or becoming distorted by the action of the material being forced away from the screw or plodder.

A screen or strainer 32 is interposed between the shoulder 13 and the plate 29 when the members 4 and 19 are assembled.

20 The movable member 19 is removably secured to the fixed member by means of a series of bolts 33, each of which is provided with a head 34 mounted to swing on a pivot 35 carried by ears 36, 37 radially disposed on the periphery of the face plate 6, and the threaded outer end of each 25 bolt is arranged to move into and out of a pair of lugs 38, 39 extending outwardly from the movable member 19. A washer 40 and a nut 41 are disposed on the bolt, with the washer in position to engage the lugs 38, 39, so that, as the nut 30 is screwed on its bolt, the member 19 by means of its lugs will be drawn toward the member 4 until the plate 29 causes the screen 32 to be seated and tightly held upon the shoulder 13.

35 The member 19 is adapted to be swung into and out of engagement with the member 4, when the bolts are released from the lugs 38, 39, by means of a hinge formed by knuckles 42, 43 on the movable member 19 loosely mounted on 40 pins 44, 45 which are fixed in projections 46, 47 extending laterally from the side of the fixed member 4.

In order that the material extruded may be cut transversely at the point of delivery, I provide 45 a cutter 48 in the form of a wire stretched diametrically across the end of the member 19, the outer ends of which wire are secured to studs 49, 50 carried by the half-sections 51, 52 which are secured together at 53, 54 by means of bolts 55 and nuts 56 to form an annular ring. This ring is arranged to rotate in an annular groove 57 formed 50 adjacent the outer end of the member 19.

In Figs. 1 to 3 inclusive, this ring is provided 55 with a series of outwardly extending sockets 58 which are adapted to receive a pinch bar or other suitable means (not shown) for manually moving the ring in its groove and the cut-off wire 48 across the outlet of the movable member.

60 In Figs. 4 and 5 there is shown a modified form of severing means which comprises a cut-off wire 59 having its ends fixed to studs 60, 61 carried by a ring gear 62 arranged to rotate in an annular recess 63 on the movable member 64 of the head. 65 This ring gear 62 is retained in the recess 63 by means of an annular ring 65 secured to the end of the member 64 by screws 66. The ring gear 62 is arranged to mesh with a pinion 67 mounted on one end of a shaft 68 journaled in the bearing 69 on the member 64. The other end of the shaft 70 70 is provided with a spiral gear 70 which coacts with the spiral gear 71 mounted to rotate on a hinged pin 72 fixed in the knuckle 73 on the hinge. Arms 74, 75 extend from the knuckle 73 in position 75 to form the journal for a drive shaft 76 hav-

ing keyed thereon a spiral gear 77 which meshes with the spiral gear 71.

In operation: The material to be strained, such, for instance, as ground up or masticated old rubber products, and the like, is urged forwardly 5 by the screw 2, passed into the flared chamber in the fixed member 4 of the head immediately in front of the screw, then through the screen 32 and holes 30 in the plate 29 and then through the flared outlets adjacent thereto in the movable member 19, where it is divided longitudinally 10 into four sections by the vertical and horizontal partitions. The passage of the material from the screw into the adjacent chamber is more rapid than its movement from the plate 29 into the divided outlet because of the obstruction provided by the said plate. The provision of the abruptly flared chamber between the screw and screen, and the less abruptly flared outlets conform the device to this condition. Additionally, the fact that the 20 screen is of much greater cross sectional area than the screw receiving portion lends to the increase in output of the device by permitting the screw to work out or near its capacity instead of hampering it by back pressure upon the material. 25 After a certain amount of material has been strained, it may be found desirous to clean or remove the screen or plate and, in order to bring the screen to a position to be operated upon, the nuts 41 and washers 40 on the bolts 33 are backed 30 off away from the lugs 38, 39 on the movable member 19, so that the bolts 33 may be swung outwardly on their pivots 35 from between the lugs, whereupon the movable member 19 may be swung outwardly on its hinges away from the fixed member 4, as shown in dotted outline in Fig. 1.

When the member 19 has been moved away from the fixed member, the full surfaces of the screen 32 and plate 29 are exposed so that any cleaning or removal which may be required is 40 readily and easily accomplished. After the screen or plate has been cleaned or renewed and returned to its former position, the member 19 is again swung on its hinges into engagement with the fixed member, and the bolts 33 replaced between the lugs 38, 39, so that the nuts and washers 45 may be screwed into contact with the lugs until the member 19 is rigidly secured to the member 4, whereupon the machine is again placed in condition for further operation.

When it is desired to cut the material passing from the outlets in the movable member 19 into predetermined lengths, the operative causes the wire cutter to be moved in a plane transversely to the movement of the material. In Figs. 1 to 3 55 inclusive, the wire cutter 48 is actuated by inserting a pinch bar or other suitable tool in one of the sockets 58 in the split ring, and the split ring rotated in its annular groove 57 at least one-half a revolution. By reason of the wire 48 60 being stretched between studs 49, 50 which are disposed in the ring at diametrically opposite points and the ring rotated, the wire will be caused to move transversely across the outlets in the movable member and thereby cut the material 65 passing outwardly therefrom.

In Figs. 4 and 5 the severing means 59 is actuated by the movement of the ring gear 62 in its annular recess 63 in the movable member 64, which movement of the ring gear is motivated 70 from a source of power (not shown) applied to the shaft 76 having keyed thereon a spiral gear 77 which transmits its motion to the spiral gear 71 loosely mounted on the hinged pin 72 of the knuckle 73, which gear 71, in turn, moves the 75

spiral gear 10 and the shaft 68 having the pinion 67 thereon, which pinion 67 meshes with the ring gear 62.

The construction above described enables the members forming the strainer head to be separated and replaced; such removal being accomplished in a ready and expeditious manner. The readjustment of the parts in the exactly desired positions is readily assumed. The device is of simple character, easily manufactured, and readily adapted to a strainer or approved extruding machine.

It will be understood that various changes may be resorted to in the form, construction and arrangement of the several parts without departing from the spirit and scope of my invention, and hence I do not intend to be limited to the details herein shown and described, except as they may be included in the claims.

20 What I claim is:

1. In combination with the cylinder and screw of an extruding machine, a head comprising fixed and movable members hinged together, each member having an opening therethrough for the passage of the material, said opening in the fixed member being abruptly flared immediately in advance of the screw receiving portion of the member and the opening in the movable member slightly flared outwardly therefrom, said movable member having diametrically opposed partitions in the flared opening, a relatively thin strainer plate interposed between the members in position to be reinforced and supported against lateral distortion by said partitions, and means movable on the fixed member and adapted to engage the movable member for locking the members together.

2. In combination with the cylinder and screw of an extruding machine, a head comprising fixed and movable members hinged together, each member having an opening therethrough for the passage of the material, said opening in the fixed member being abruptly flared immediately in advance of the screw receiving portion of the member and the opening in the movable member slightly flared outwardly therefrom, said movable member having diametrically opposed partitions in the flared opening, a relatively thin strainer plate interposed between the members in position to be reinforced and supported against lateral distortion by said partitions, and means movable on the fixed member and adapted to engage the movable member for locking the members together.

3. In combination with the cylinder and screw of an extruding machine, a head comprising fixed and movable members hinged together, each member having an opening therethrough for the passage of the material, said opening in the fixed member being abruptly flared immediately in advance of the screw receiving portion of the member and having a shoulder formed therein adjacent the outer end of the abruptly flared opening, said opening in the movable member being slightly flared, said movable member having diametrically opposed partitions in the flared opening, a relatively thin strainer plate interposed between the members and seated against said shoulder in position to be reinforced and supported against lateral distortion by said partitions, and means movable on the fixed member and adapted to engage the movable member for locking the members together.

75 4. In combination with the cylinder and screw

of an extruding machine, a head comprising fixed and movable members hinged together, each member having an opening therethrough for the passage of the material, said opening in the fixed member being abruptly flared immediately in advance of the screw receiving portion of the member and having a shoulder formed therein adjacent the outer end of the abruptly flared opening, said opening in the movable member being slightly flared, said movable member having diametrically opposed partitions in the flared opening, a relatively thin strainer plate interposed between the members and seated against said shoulder in position to be reinforced and supported against lateral distortion by said partitions, said strainer plate being removably secured to the movable member, and means movable on the fixed member and adapted to engage the movable member for locking the members together.

5 5. In an extruding machine, the combination with the cylinder and screw, of a head comprising a member fixed to the cylinder and a member hinged to swing toward and away from the fixed member, said fixed member having a longitudinal bore for the end of the screw, a chamber adjacent the end of the screw, the walls of said chamber being abruptly flared outwardly from the bore of the cylinder, said movable member having an opening for the passage of the material therethrough, the interior diameter of said opening being substantially equal to the outer diameter of the flared chamber and slightly flared outwardly, a strainer plate interposed between the members and adjacent the flared chamber, and means for locking the members together.

10 6. In an extruding machine, the combination with the cylinder and screw, of a head comprising a member fixed to the cylinder and a member hinged to swing toward and away from the fixed member, said fixed member having a longitudinal bore for the end of the screw, a chamber adjacent the end of the screw, the walls of said chamber being abruptly flared outwardly from the bore of the cylinder, said movable member having an opening for the passage of the material therethrough, the interior diameter of said opening being substantially equal to the outer diameter of the flared chamber and slightly flared outwardly, a strainer plate removably secured to the interior face of the movable member in position to span the flared chamber when the members are assembled, and means for locking the members together.

15 7. In an extruding machine, the combination with the cylinder and screw, of a head comprising a member fixed to the cylinder and a member hinged to swing toward and away from the fixed member, said fixed member having a longitudinal bore for the end of the screw, a chamber adjacent the end of the screw, the walls of said chamber being abruptly flared outwardly from the bore of the cylinder and terminating in an annular recess, said movable member having an opening for the passage of the material therethrough, the interior diameter of said opening being substantially equal to the outer diameter of the flared chamber and slightly flared outwardly, a strainer plate disposed in said recess and interposed between the members when assembled, and means for locking the members together.

20 8. In an extruding machine, the combination with the cylinder and screw, of a head comprising a member fixed to the cylinder and a member

hinged to swing toward and away from the fixed member, said fixed member having a longitudinal bore for the end of the screw, a chamber adjacent the end of the screw, the walls of said chamber being abruptly flared outwardly from the bore of the cylinder and terminating in an annular recess, said movable member having an opening for the passage of the material therethrough, the interior diameter of said opening being substantially equal to the outer diameter of the flared chamber and slightly flared outwardly, a strainer plate removably secured to the interior face of the movable member in position to seat in said recess when the members are assembled, and means for locking the members together.

9. In an extruding machine, the combination with the cylinder and screw, of a head comprising a member fixed to the cylinder and a swinging member carried by the fixed member, said fixed member having a longitudinal bore for the end of the screw, a foraminous plate and straining screen carried by the head in spaced relation

to the front end of the screw and in spaced relation to the front end of the swinging member so as to form chambers for the passage of the extruded material on each side of the foraminous plate, the diameter of said chambers being greater than the diameter of the screw bore, means for locking the fixed and swinging members together, an annular support mounted at the front end of the swinging member, an elongated severing member of such small cross-sectional dimension as to offer no substantial resistance to the extrusion of the material and to be adapted to cut the material both longitudinally and transversely, said severing member being free of supporting or reinforcing means intermediate its ends and being fixedly secured at both its ends to said annular support, and means for rotating said annular support so as to twist said severing member about an imaginary point substantially in line with the axis of extrusion for periodically transversely cutting the extruded material upon a diametrical line.

VERNON ROYLE.
